AIRPLANE DESCRIBING SYSTEM

Frederick W. Brixner, Gates, N. Y., assignor to
General Railway Signal Company, Rochester,
N. Y.

Application June 4, 1938, Serial No. 211,961

14 Claims.

(Cl. 177—333)

The present invention relates to a system for describing the character of airplanes, such as passenger or mail, and the route over which they fly as well as the elevation at which they are instructed to fly as they enter an air port.

With the growth of airplane traffic and the advancement that has been made in blind flying, that is flying wholly by instruments in case of fog, and for other reasons, it is important to have airplanes which arrive at the same air port to fly at definite altitudes during their wait for permission to make a landing. For instance, if there are three airplanes arriving at the same air port at substantially the same time, it is important that these airplanes be instructed to enter such port at definite elevations, the first plane to make a landing being instructed to take the lower of three elevations, and the plane instructed to land last being instructed to take the highest elevation as it enters the port. In practice it is found that the airplane dispatcher, the man who is in telephonic communication with airplanes equipped with wireless telephones and who is in communication with airplanes not so equipped by code flashes of light of various colors given in different combinations or order, must be located so as to be able to view the entire surrounding sky. For this reason he is preferably located in a tower having a glass dome roof to give him the necessary visibility of all incoming planes.

In the more crowded air ports it is found that an attendant known as a "plane dispatcher" is kept busy by keeping his eyes on the field and by giving instructions and receiving reports to and from approaching airplanes. For this reason it is necessary that another person, preferably his superior, who has been designated a "traffic manager" in this application, assumes the responsibility of determining which of several airplanes approaching the air port shall have priority over the other planes and shall for this reason come in at a lower altitude than any of said other planes. In other words, the entire work must of necessity be divided between at least two men. In order that each man may know what the other man is doing it is proposed, in accordance with the present invention, to employ a suitable illuminated board which not only defines the plane by its character or route but also defines the altitude at which the plane is permitted to fly into and over the air port. This board or boards depending upon whether the two men are in the same or different rooms, must be visible and controllable by both men in a manner so

that inconsistent indications cannot be given, and so that an indication displayed by the movement of a key on one panel may be extinguished by the movement of a key on the other panel, and at the same time leave the apparatus in such condition that the indication may again be displayed by the operation of the key on said one panel. Another object of the present invention is to so divide the work between the traffic manager and the plane dispatcher, by the provision of suitable apparatus, that each may give information to the other without the use of a telephone or direct conversation, and in a manner so that these informations cannot be inconsistent. Another object of the present invention is to so divide the work between the traffic manager and the plane dispatcher that the traffic manager need not have a view of the flying field or air port, his information being entirely derived from a loud speaker which announces all of the telephonic communications between the plane dispatcher and the pilots of the various planes in addition to that derived from the indication board located in his office which is in part controlled by himself and in part controlled by the plane dispatcher.

Other objects, purposes and characteristic features of the present invention will be in part described as the specification progresses and will in part be obvious from the accompanying drawings which form a part of this application.

In these drawings Fig. 1 illustrates a side elevation of the plane dispatcher's office, which office is provided with a glass dome giving the plane dispatcher an unobscured view of the sky and field of the entire air port and below which is shown in the traffic manager's room containing the apparatus necessary for the traffic manager to perform his duties in connection with the arrival of planes.

Fig. 2 shows the various circuits and apparatus for controlling the lamps of the "elevation" portion of the indicating boards located in the plane dispatcher's and the traffic manager's offices; and

Fig. 3 shows the circuits and apparatus for controlling the indicators of the "identification" portion of the plane dispatcher's board and the traffic manager's board.

Apparatus

Referring to Fig. 1, the building 1 illustrated may for convenience be called the traffic office of an air port. As illustrated, this building includes a suitable tower, preferably round in con-

struction and comprising a glass dome 2, to render the entire landing field or air port as well as the sky above and surrounding it visible to the plane dispatcher located in this tower designated PDT. Directly below this plane dispatcher's tower has been illustrated a room for housing the traffic manager and his apparatus which is known as the traffic manager's office and designated TM. Directly below the room TM and possibly in the basement of the building has been shown a relay cabinet for housing the relays of the control system shown in Figs. 2 and 3 of the drawings.

Referring to the plane dispatcher's tower PDT, this tower is provided with a plane dispatcher's board PDB which is divided into two parts, the upper one designated "elevation," and the lower part designated "indications." Although any desired type of electrically operated indicators may be used, the present invention for convenience illustrates lamps for identifying the planes and their elevation, and hereinafter the word lamp is to be understood as one form of indicator. As illustrated there are six vertical rows of lamps shown in the upper or "elevation" portion of the plane dispatcher's board PDB, each row including six lamps designated 1000, 2000, 3000, 4000, 5000 and 6000, respectively. Each of these lamps when energized indicates that the plane identified by that column has been instructed to fly at an elevation in feed corresponding to the number identifying that lamp. In other words, if the lamp 2000 of column 1 is illuminated, as illustrated, this signifies that the plane identified by column 1 has been instructed to fly at an elevation of 2000 feet. The same thing is true of the next five vertical columns of lamps. The first two columns of lamps have been designated X¹ and X². These two columns of lamps are employed for identifying the planes and the elevations at which they are instructed to fly which arrive over route X. The planes, separate from their elevation, are characterized or defined in the "indication" portion of the boards by the lamps A, B or C located in the corresponding column. For instance, the energized lamp A in column X¹ signifies that a plane of type A¹, such as a limited passenger plane, a local passenger plane, or a mail plane, is arriving on route X¹ and the illumination of lamp 2000 manifests that this plane has been instructed to arrive at an elevation of 2000 feet. In column X² the lamps B² and 4000 have been illustrated illuminated. This means that there is also arriving a plane B¹ on route X² and that this plane B¹ has been instructed to fly at an elevation of 4000 feet. Referring for a moment to the map located on the desk in the traffic manager's office TM, these planes A¹ and B¹ are shown on this map by miniature airplanes laid on the line of route X. Since plane A¹ is ahead of plane B¹ the plane A¹ has been instructed to fly at a lower level than has plane B¹, so that the plane A¹ may make a landing without passing through the elevation or zone occupied by plane B¹. This map also shows a route Y which is not at this time occupied by any plane, and for like reasons the lamps in columns Y¹ and Y² on the plane dispatcher's board PDB and the traffic manager's board TMB are not lighted. Referring again to this map on the traffic manager's desk the plane C¹ arriving on route Z is evidently a first class plane and should have preference over the planes A¹ and B¹ on route X. For this reason the plane C¹ has been iden-

tified in column Z¹ by the illumination of the lamp C, and the elevation at which this first class plane C¹ is permitted to enter the airport is indicated by the illumination of the lamp 1000 on the two boards PDB and TMB. It is apparent that this first class plane C¹ may land first because it enters the air port at a lower elevation than do either plane A¹ or B². As illustrated the boards PDB and TMB are preferably identical and corresponding lamps on the two boards are preferably connected in series, so that the accidental breaking of a circuit or the burning out of one lamp will cause the other lamp to likewise be extinguished, so that these boards at all times display the same indications.

Referring again to the plane dispatcher's tower PDT, the plane dispatcher is preferably provided with a radio telephone Tel preferably located on his desk, on which desk are also mounted elevation keys X¹, X², X¹, X², K¹, K² and a cancelling push button CPB. On the wall of the plane dispatcher's tower is preferably located a call lamp CL and a call bell CB. If this lamp CL or bell CB is rendered active the same may be rendered inactive by pressing the cancelling push button CPB. This lamp CL and bell CB is rendered active each time that an additional plane has been identified in the plane dispatcher's tower by the operation of a manually operable push button PB on the traffic manager's panel TMP located in the traffic manager's office TM, as more specifically described hereinafter.

In the traffic manager's office TM is provided a desk containing a map of the surrounding country illustrating the various air routes terminating at the air port shown by a circle AP. As above mentioned the traffic manager's office is provided with a loud speaker LS illustrated on the wall in the traffic manager's office TM, which loud speaker announces the conversations in both directions between the plane dispatcher and the pilots of the various planes equipped with wireless telephony. When a plane approaches, which is not equipped with a telephone, the plane dispatcher will report this fact to the traffic manager through the medium of this same telephone Tel and loud speaker LS. On the traffic manager's desk is also located the traffic manager's panel TMP. This panel is divided into two parts, as illustrated, the upper part being provided with six rows of push buttons, there being six push buttons in each row corresponding to the lamps in the "elevation" portion of the boards PDB and TMB. These push buttons have been designated PB¹ to PB⁶ successively as shown for the push buttons in the third column and as designated in Fig. 2 of the drawings. Depression of the push button PB⁶ for the third column of push buttons will cause the lamp 6000 in column Y¹ of each of the boards PDB and TMB to be illuminated, all in a manner more specifically described hereinafter in connection with Fig. 2 of the drawings. The lower part of the traffic manager's panel TMP contains six rows of push buttons, there being three push buttons in each row. The push buttons of the third column have been designated PB^A, PB^B and PB^C, and these push buttons are also illustrated in Fig. 3 of the drawings. The depression of the push button PB^A for column 3, for instance, will cause the lamp A in the column Y¹ of each of the boards PDB and TMB to be illuminated.

Let us now briefly consider the arrival of a plane at the airport and the manner in which

this plane is instructed to land without considering the detailed apparatus and circuits involved in giving this instruction. Let us assume that the traffic manager is occupying his stool TMS and that the plane A¹ on route X has been reported to be located at a certain point on route X and approaching the air port. The traffic manager being aware of the fact that the plane C¹ on route Z is a superior plane he will reserve the 1000 feet elevation for the plane C¹ and accordingly will depress the push button PB⁴ in the first column and simultaneously therewith will depress the push button 2000 in the first column. This manipulation on the part of the traffic manager will light the lamps A and 2000 in column X¹ on both of the panels PDB and TMB. The traffic manager being aware of the fact that the plane C¹ is superior will substantially simultaneously also press the push button 1000 and PB^C in the fifth column, thereby illuminating the lamps 1000 and C in column Z¹ on the boards PDB and TMB. This manipulation on the part of the traffic manager will also sound the call bell CB and illuminate the lamp CL in the plane dispatcher's office PDT. The plane dispatcher having been warned that new indications have appeared on his board will look at his board and depress the cancel push button CPB so as to extinguish the call light CL and render the call bell CB no longer audible. The plane dispatcher will then look out over the field and even though he sees the plane A¹ approaching on route X he is aware of the fact that the plane which will sooner or later approach on route Z is the first one to be landed and accordingly he will give instructions to the plane A¹ on route X¹ to cruise over the field at an elevation of 2000 feet. The plane dispatcher will then keep a look-out for the arrival of plane C¹ on route Z¹. As soon as this plane C¹ on route Z¹ arrives the plane dispatcher PDB will give instructions by telephone to the pilot of this plane informing him that he is to arrive at an elevation of 1000 feet and to make a landing upon reaching the field. As soon as the plane C¹ which arrived on route Z has made its landing the plane dispatcher will operate his key K^{Z1} to the lower position and back to the middle position. This will cause the lamp 1000 in column Z¹ to be extinguished on both of the two boards PDB and TMB. Had it not been the lowermost lamp in the elevation portion of the column the next lower lamp would have been lighted. For reasons pointed out hereinafter the identification lamp C in column Z¹ will also be extinguished. The plane dispatcher, who may be occupying the stool PDS, will then instruct by wireless telephony the pilot of the plane A¹ on route X to come down to a level of 1000 feet and immediately upon giving such instruction he will operate his key K^{X1} to the lower position and back to the middle position, this will cause the lamp 2000 in column X¹ to be extinguished and the lamp 1000 in column X¹ on boards PDB and TMB to be illuminated.

Control apparatus

In Fig. 2 has been illustrated the control apparatus for controlling the "elevation" portion of the boards PDB and TMB. For convenience only the control devices, relays and lamps for the column Y¹ have been illustrated. Likewise, only the control circuits and apparatus for the lamps A, B and C in column Y¹ have been shown in Fig. 3 of the drawings.

Referring to Fig. 2 of the drawings the key 75

K^{Y1} shown in Fig. 2 is the key K^{Y1} shown on the plane dispatcher's desk in Fig. 1 of the drawings. Likewise, the push buttons PB¹ and PB⁶ in Fig. 2 are the push buttons correspondingly designated in the third column on the traffic manager's desk in Fig. 1 of the drawings. The left hand row of lamps 1000, 2000, 3000, 4000, 5000 and 6000 of Fig. 2 are the lamps correspondingly designated and shown in column Y¹ on the plane dispatcher's board PDB in Fig. 1, whereas the right hand row of lights 1000, 2000, 3000, 4000, 5000 and 6000 are the correspondingly designated row of lights indicated in the row Y¹ on the traffic manager's board TMB shown in Fig. 1 of the drawings. For each elevation indicating lamp on either of the boards PDB or TMB is provided a stepping relay V. These stepping relays for lamps 1000 to 6000, respectively, of column Y¹ of Fig. 1 have been designated V1 to V6, respectively, in Fig. 2. These stepping relays are so interconnected in the circuit that a particular relay cannot be energized unless all of the relays of lower order are energized. For instance, the relay V3 cannot be picked up unless the relay V2 is in its picked up condition, and the relay V2 cannot be picked up unless the relay V1 is picked up. These stepping relays may be initially controlled by the push buttons PB¹ to PB⁶, inclusive, and may thereafter be controlled through the medium of the plane dispatcher's key K^{Y1}, which key may control the stepping relays through the medium of the step control relays ED and EU and slow acting half-step relay VP. The call relay CR affords a stick feature, in that it may be picked up by the momentary depression of any one of the push buttons PB¹ to PB⁶, inclusive, and remains stuck up until the cancelling push button CPB on the plane dispatcher's board has been depressed. This call relay CR when energized illuminates the call lamp CL, and sounds the call bell CB, both located in the plane dispatcher's office.

As heretofore pointed out none of the stepping relays V2 to V6 may be picked up unless all of the stepping relays of lower order are energized. By examining the pick-up circuit for the stepping relay V1 it is apparent that this pick-up circuit can only be closed by one of the push buttons PB¹ to PB⁶, inclusive. It is thus apparent that the energization of a relay V and the illumination of its associated lamps is only possible by the operation of a push button PB located in the traffic manager's office, and that the plane dispatcher cannot by his keys K^{X1} to K^{Z1} cause the initial energization of a plane elevation indicating lamp 1000 to 6000. The half-step relay VP performs very much the same function as does a half-step relay in any stepping relay bank, in that it transfers the pick-up and stick circuits from one to another pick-up or stick bus respectively. It will be noted that this relay VP is provided with a stick contact 3 and two control contacts 4 and 5, respectively. In order to simplify the circuit arrangement illustrated in the drawings, the complete circuits including a battery have not been illustrated and merely the terminals (+) and (-) of a suitable battery or other source of current have been shown to signify the (+) and (-) terminals of one or more batteries used in the system. Since the stick buses 8 and 9 are both connected to the (+) terminal of the battery with the step control relay ED in its retracted position it is immaterial whether or not the contact 4 of the relay VP is in its raised or lowered position.

Similarly, with the step control relay EU de-energized and its contact 73 open, it is immaterial whether or not the contact 5 of the relay VP is in its raised or lowered position, because the contact 5 of this relay VP is not connected to a source of current. In other words, the relay VP does not perform any particular function so long as the step control relays ED and EU remain deenergized, and we need not consider the relay VP in the discussion of the control of relays V by the push button PB¹—PB⁶. The step control relay ED signifies by its letter D that it is employed for stepping the relays V down to a lower order, and the letter U of the reference character EU signifies that this relay EU when energized causes the stepping relays V to step up to a higher order, that is, the letter D signifies "down" and the letter U signifies "up."

Let us now observe how depression of the push button PB⁶ will cause all of the stepping relays V1 to V6 to be picked up and how this causes the two lamps 6000 only to be energized. Depression of the push button PB⁶ closes the pick-up circuit for the lower winding of the relay V1 from the terminal (+) through the bus wire 10, the contact of push button PB⁶, the bus wire 12, the lower winding of the relay V1 to the other terminal (—) of the same source. This causes the relay V1 to assume its picked up position thereby closing its contacts 13, 14, 15 and 16. With the contact 13 of stepping relay V1 closed a pick-up circuit for the relay V2 is closed from battery (+) through bus wire 10, contact of push button PB⁶ to wires 17 and 18, 35 back contact 19 of relay V5, wire 20, back contact 21 of relay V3, wire 22, front contact 13 of relay V1, wires 23 and 24, winding of the relay V2, to the other terminal (—) of the same source. With the relay V2 picked up its contacts 25, 26, 27, 28 and 29 are closed. The closure of contact 26 of relay V2 closes a stick circuit for the lower winding of the relay V1. Also, the closure of its stick contact 28 closes a stick circuit for the relay V2 including this stick contact 28, the front contact 15 of relay V1 and the back contact 31 of the relay ED.

With the stepping relay V2 now energized a pick-up circuit is closed for the lower winding of the stepping relay V3, which circuit includes the contact of the push button PB⁶, the back contact 35 of the relay V4 and the front contact 25 of the relay V2. The closure of this circuit picks up the relay V3 thus resulting in closure of its front contacts 21, 36, 37, 38 and 39. The closure of its stick contact 38 closes its stick circuit including this contact, the front contact 29 of relay V2 and the back contact 4 or 30 of the relay VP or ED, respectively. Also, with this relay V3 picked up a pick-up circuit is closed for the relay V4 which includes a contact of the push button PB⁶, the back contact 19 of relay V5, and the front contact 21 of relay V3. With the relay V4 picked up in response to the closure of this pick-up circuit, it closes the front contacts 35, 41, 42, 43 and 44 of this relay V4, and in turn closes the stick circuit for this relay V4 including its stick contact 43, the front contact 39 of relay V3 and the back contact 31 of relay ED. With the stepping relay V4 energized a pick-up circuit is closed for the stepping relay V5 which includes a contact of the push button PB⁶, and the front contact 35 of relay V4. Picking up of the relay V5 closes its front contacts 19, 46, 47, 48 and 49.

The closure of its stick contact 48 closes a stick circuit for this relay V5 which includes this stick contact 48, the front contact 44 of relay V4 and the back contacts 4 and 39 of the relays VP and ED in multiple. With the stepping relays V5 now picked up a pick-up circuit is closed for the stepping relay V6 through the front contact 19 of relay V5 and the contact of push button PB⁶. The picking up of this stepping relay V6 opens its back contact 51 and closes its front contacts 52, 53 and 54. The closure of its contact 54 closes a stick circuit including this stick contact 54, the front contact 49 of relay V5 and the back contact 31 of relay ED. It may be pointed out that the picking up of each of relays V2 to V6, inclusive, completed a stick circuit for its next preceding relay. These stick circuits include the lower windings of these relays and may be readily traced in the drawings. Also, as these relays V1, V2, V3, V4, V5 and V6 are successively picked up the relay VP was successively picked up and dropped, one movement for each relay operation. The relay VP was picked up in response to picking up of the relay V1 through a circuit including back contacts 60, 61, 62, 63, 64, 65 and 66 of relays EU, ED, V6, V5, V4, V3 and V2, respectively, and the front contact 67 of the relay V1. By looking at this pick-up circuit for the relay VP it is readily observed that a pick-up circuit is closed each time that an odd stepping relay is picked up and is dropped each time that an even stepping relay is picked up. The depression of the push button PB⁶ also closes an energizing circuit for the call relay CR readily traced in the drawing, which relay CR is then stuck up through its stick contact 68. The successive picking up of these stepping relays through the medium of contacts 50, 55, 56, 57, 58 and 59 causes successive illumination of the lamps 1000, 2000, 3000, 4000, 5000 and 6000, in column Y¹ in the order given, only one of these pairs of lamps being energized at one time, and the lamps 6000 only remaining energized. The traffic manager having once depressed the push button PB⁶ cannot thereafter change his indication to one signifying a lower traffic level. Had the traffic manager depressed the push button PB⁵ he could thereafter have changed this indication to one signifying higher level, this being accomplished, for instance, by depression of the push button PB⁶, all as is obvious from the circuits illustrated in Fig. 2 of the drawings and described above.

Let us now assume that the lamps 6000 in column Y¹ on both of the boards PDB and TBB are illuminated and that the plane dispatcher desires to have the plane identified by the lamps in column Y¹ to fly at an elevation of 5000 feet. The plane dispatcher will first inform the pilot of this plane by telephone that he is to fly at an elevation of 5000 feet. He will then operate his key K^{Y1} (see Figs. 1 and 2) to its lower position, thereby closing an energizing circuit for the relay ED. Since with the relay V6 picked up the relay VP is deenergized we must bear in mind that the contacts 4 and 5 of this relay VP assume their lower position. The picking up of the relay ED will open its back contacts 30, 31, 61 and 71. The opening of back contact 71 will open the stick circuit for the lower winding of the relay V6, the opening of the contact 31 will open the stick circuit for the upper winding of the relay V6, as a result of which the relay V6 will assume its retracted position, because its

pick-up circuit has been opened by the release of the push button PB^6 in response to the illumination of the lamp 6000. Dropping of the relay $V6$ will cause closure of its back contact 62, but energization of the relay VP will not take place because the pick-up circuit is open at back contact 61 of relay ED . The plane dispatcher will, of course, return his key K^{Y1} to its middle position thereby deenergizing the relay ED which results in closure of the pick-up circuit for relay VP . With relay VP assuming its raised position the contacts 4 and 5 assume their attracted position. Let us now assume that the plane dispatcher desired to have the plane under consideration fly at an elevation of 4000 feet instead of 5000 feet. He will so inform the pilot by telephone and upon completion of the instructions he will again depress his key K^{Y1} resulting in the picking up of the "down" relay ED . Since the relay VP is now energized the stick circuit for the stepping relay $V5$ is dependent for its energization on a closed back contact 30 of relay ED , the back contact 4 of the relay VP now being open. Picking up of the relay ED will therefore break the stick circuit for the upper winding of the relay $V5$, and since the stick circuit for the lower winding of relay $V5$ is broken at the front contact 52 of the relay $V6$ and the pick-up circuit for the lower winding of the relay $V5$ is open at the back contact 5 of the relay VP , this stepping relay $V5$ will now assume its retracted position, thereby extinguishing its lamp 5000 in the column Y^1 of boards PDB and TMB and instead illuminating the lamp 4000 in this same column. In a similar manner the relays may be dropped from any particular order to the next lower order by momentarily operating the key K to its lower position and returning it to its intermediate position.

Let us now observe how the plane dispatcher may change an indication identifying a particular elevation a plane may fly to a lamp identifying a higher elevation. This is done by momentarily operating the key K^{Y1} to its raised position and then returning it to its intermediate position. With the lamp 4000 in column Y^1 still illuminated, that is, with the relays $V1$, $V2$, $V3$ and $V4$ all energized and the relays $V5$ and $V6$ deenergized we will also note that the relay VP is deenergized under this condition. The movement of the key K^{Y1} to its raised position will cause the "up" relay EU to pick up. Since the relays VP and $V6$ are both deenergized and the relay EU is now energized, a pick-up circuit for the relay $V5$ is closed which may be traced as follows: starting from the (+) terminal of the battery, front contact 73 of relay EU , back contact 5 of relay VP , back contact 51 of relay $V6$, front contact 35 of relay $V4$, through the lower winding of the relay $V5$ to the other terminal (-). The closure of this circuit will cause the relay $V5$ to pick up thereby closing its stick circuit including its stick contact 48, front contact 44 of relay $V4$, and the back contacts 30 of the relay ED and 4 of relay VP in multiple. The picking up of this relay $V5$ will cause the relay VP to be picked up as soon as the relay EU is deenergized in response to return of the key K^{Y1} to its intermediate position. This picking up of the relay VP will, however, not have any effect on the stepping relays V , because both back contacts 30 and 31 of relay ED maintain the various stick circuits for the upper winding of the relays $V1$ to $V5$, inclusive, closed. Also the picking up of relay VP will not result in the energization of relay $V6$, because contact 73 dropped 75

before contact 5 was picked up in the pick-up circuit of relay $V6$.

It is thus seen that the plane dispatcher cannot light a lamp in a dark column of the elevation portion of the board, but can merely change the indication from one elevation to another, and that for each momentary depression of the key K the next lower lamp for that column is lighted and that for each momentary lifting of the key the next higher lamp of that column is lighted. Also, if all the lamps of a column have once been extinguished, by operation of push button K^{Y1} to deenergize relay $V1$ by the plane dispatcher, he cannot restore an indication in that column because there is no pick-up circuit for the relay $V1$ which does not include a push button contact located on the traffic manager's panel TMP.

Control apparatus for the plane identifying lamps

As heretofore pointed out the depression of any one of the push buttons PB^A , PB^B and PB^C illustrated on the traffic manager's panel in room TM will cause the corresponding lamps A, B or C for the column Y^1 to be illuminated. These push buttons PB^A , PB^B and PB^C are also shown in Fig. 3 of the drawings, as are also the lamps A, B and C located in column Y^1 of the indicating boards PDB and TMB located in the plane dispatcher's room and the traffic manager's room, respectively. Referring to Fig. 3, it will be noted that the lamps A on the two boards will be energized when the relay AR alone is energized, that the lamps B will be energized when the relay BR alone is energized, and that the lamps C will be energized when the relays AR and BR are both energized. Also, it is readily apparent from the circuit shown in Fig. 3 that depression of the push button PB^A closes a pick-up circuit for relay AR , that the depression of the push button PB^B will result in closing a pick-up circuit for the relay BR , and that depression of the push button PB^C will result in closure of the pick-up circuits for both of the relays AR and BR . Also, it is apparent from these circuits for relays AR and BR that stick circuits for these relays will be closed as soon as these relays pick up, providing that the stepping relay $V1$ for the corresponding column Y^1 is in its attracted condition. This is true because the stick circuit for the relay BR , for instance, includes the front contact 34 of the stepping relay $V1$ (see Figs. 2 and 3) and includes the stick contact 74 of the relay BR (see Figs. 2 and 3). It is thus seen that the depression of the push buttons PB^A , PB^B or PB^C will cause the temporary illumination of the lamps A, B or C for the column Y^1 of the indicating boards, and that the particular indication will be retained only if the stepping relay $V1$ is energized. It should be remembered that relay $V1$ will be up if any one of the six elevation indicating lamps for that column is illuminated. In other words, if the traffic manager depressed any one of the push buttons PB^1 to UB^6 of column Y^1 simultaneously with the depression of push button PB^A he will cause the A lamp in column Y^1 to be permanently energized with the temporary energization of one of the lamps 1000-6000 in this same column. The energization of the elevation lamps 1000-6000 is said to be temporary because the plane dispatcher may switch from one lamp to another, and the energization of the plane identifying lamp is said to be permanent because the plane dispatcher can only cancel it. It is, of course, understood that the circuit dia-

grams and associated apparatus shown in Figs. 2 and 3 is duplicated for each of the six columns on the indication boards. Also, what has been said about the control of lamp A is true of lamps B and C.

Although the indication boards have been illustrated as being mounted on the wall and away from the control panels it is to be understood that the plane dispatcher's control panel may be directly associated with his indicating board so that each of his control keys K are located directly below the corresponding column of lamps or indicators. Similarly, the indication board TMB located in the traffic manager's office may be directly associated with his control panel TMP, 15 so that each of his rows of push buttons PB is located directly under the column of lamps or indicators for that column on his board TMB. Also, it is to be understood that in those cases where both the traffic manager and the plane dispatcher are located in the same office a single indication board mounted so as to be viewable by both of these men may suffice, and that in this case each of these men will have readily accessible his own particular control panel so that both of these control panels may be used to control a single indication board. Also, it is to be understood that the plane dispatcher will be provided with suitable signal lamps to transmit information to pilots flying planes which are not equipped with radio apparatus, and in this case the plane dispatcher will speak into his telephone instrument the instructions transmitted by light signals to the unequipped plane, so as to inform the traffic manager through the medium of the 35 same loud speaker LS the instructions given to such an unequipped plane. As shown in Fig. 1 the various panels, boards and relay cabinet are connected by conduits to facilitate wiring.

The applicant has thus disclosed a specific embodiment of apparatus embodying the invention as illustrative of apparatus which may be employed to carry out his invention, and it is to be understood that this disclosure is an exemplification of apparatus that may be employed to carry 45 out this invention and is not to be taken in a limiting sense, in that numerous modifications, adaptations and additions may be made without departing from the spirit or scope of this invention except as demanded by the scope of the following 50 claims.

What I claim as new is:

1. In combination; an indicating board divided into two portions, plane identifying indicators on one of said portions and plane elevation indicators on the other of said portions, a series of stick relays with one relay for each of said plane elevation indicators, another stick relay for one of said plane identifying indicators, and a stick circuit for said other stick relay including a contact which is open only if all of the stick relays of said series are in their retracted condition.

2. In combination; an indicating board; a series of lamps, varying from lowest to highest order on said board; two control panels; a series of push button contacts, one for each lamp, on one panel and two contacts on the other of said panels; a series of relays with one relay for each of said lamps, each relay except that of the lowest order having a pick-up circuit including a front contact of the relay, of the next lower order, and, in multiple its push button contact and those of all the relays of higher order, a pick-up circuit for the first relay including its 75

push button contact; means controlled by said two contacts, respectively, to pick up a relay of the next higher order than a relay already picked up, and to drop the relay of highest order

5 then picked up, depending upon which of said two contacts is closed; and an energizing circuit for each lamp closed only if the relay associated with that lamp is in its picked up position and all the relays of higher order are in their retracted position.

3. In airplane describers, in combination, a manager's location, a dispatcher's location, a series of normally inactive indicators at the dispatcher's location, control means at the manager's location selectively operable to make any one of said indicators active, control means at the dispatcher's location operative, only if one of the indicators be active, to make any other of the indicators active while making the active indicator inactive.

4. In airplane describers, in combination, a manager's location, a dispatcher's location, a series of normally inactive indicators at the dispatcher's location, control means at the manager's location selectively operable to make any one of said indicators active, control means at the dispatcher's location operative, only if one of the indicators be active, to make any other of the indicators active while making the active indicator inactive or for making all of the indicators inactive.

5. In airplane describers, in combination, a manager's location, a dispatcher's location, a series of normally inactive indicators at the dispatcher's location, control means at the manager's location selectively operable to make any one of said indicators active, control means at the dispatcher's location operative, only if one of the indicators be active, to make any other of the indicators active while making the active indicator inactive, or for making all of the indicators inactive, the control means at the manager's location being ineffective to make an active indicator inactive without making an inactive indicator active.

6. In airplane describers, in combination, a manager's location, a dispatcher's location, a series of normally inactive indicators at the dispatcher's location, control means at the manager's location selectively operable to make any one of said indicators active, control means at the dispatcher's location operative, only if one of the indicators be active, to make any other of the indicators active while making the active indicator inactive, a like series of normally inactive indicators including an indicator corresponding with each of the indicators at the dispatcher's location at the manager's location, and circuit means connecting the corresponding indicators at the two locations in series so as to assure, at all times, the presence of identical indication aspects at the two locations.

7. In airplane describers, in combination, a manager's location, a dispatcher's location, a series of normally inactive indicators at the dispatcher's location, control means at the manager's location selectively operable to make any one of said indicators active, control means at the dispatcher's location operative, only if one of the indicators be active, to make any other of the indicators active while making the active indicator inactive, or for making all of the indicators inactive, the control means at the manager's location being ineffective to make the indicators all inactive after having made an indi-

cator active, a like series of normally inactive indicators including an indicator corresponding with each of the indicators at the dispatcher's location located at the manager's location, and circuit means connecting the corresponding indicators at the two locations in series so as to assure, at all times, the presence of identical indication aspects at the two locations.

8. In airplane describers, in combination, a manager's location, a dispatcher's location, a series of normally inactive indicators at the dispatcher's location, control means at the manager's location selectively operable to make any one of said indicators active, control means at the dispatcher's location operative, only if one of the indicators be active, to make any other of the indicators active while making the active indicator inactive, or for making all of the indicators inactive, another normally inactive indicator at the dispatcher's location, control means at the manager's location operable to make said other indicator active, the control means at the dispatcher's location being ineffective to control said other indicator except to make it inactive upon making all of said series of indicators inactive.

9. In airplane describer systems, in combination, two stations, a series of normally inactive indicators at one station, each indicator, when active, denoting a particular, and different, elevation, control means at the other station selectively operable to make any one of the indicators active, control means at said one station effective, only while an indicator is active, to make the then active indicator inactive and to make a different indicator, corresponding to either a higher or a lower elevation, active.

10. In airplane describer systems, in combination, two stations, a series of normally inactive indicators at one station, each indicator, when active, denoting a particular, and different, elevation, control means at the other station selectively operable to make any one of the indicators active, control means at said one station effective, only while an indicator is active, to make the then active indicator inactive and make a different indicator, corresponding to either a higher or a lower elevation, active, another normally inactive indicator at said one station denoting plane characteristics when active, control means at said other station for making said other indicator active, said control means at said one station operating, upon making inactive the indicator of said series denoting the lowest elevation, to make said other indicator inactive.

11. In airplane describer systems, in combination, two stations, a series of normally inactive indicators at one station, each indicator, when active, denoting a particular, and different, elevation, control means at the other station selectively operable to make any one of the indicators active, control means at said one station effective, only while an indicator is active, to make the then active indicator inactive and make a different indicator, corresponding to either a higher or a lower elevation, active, another normally inactive indicator at said one station denoting plane characteristics when active, control

means at said other station for making said other indicator active, said control means at said one station operating, upon making inactive the indicator of said series denoting the lowest elevation, to make said other indicator inactive, a like series of indicators and a like said other indicator at said other station, and means causing the indicators at the two stations to always display the identical indications.

12. In combination, an indicating board, a series of indicating lamps on said board and arranged in order from first to last, a stick relay for each lamp, a manually controllable contact for each relay, a pick-up circuit for each relay, except the first, including a front contact of the next preceding relay and, in multiple, its own manually controllable contact and those of the relays beyond it, the pick-up circuit of the first relay including its own manually controllable contact, a stick circuit for each relay including other manually controllable contacts, and a circuit for each lamp including a front contact of its relay and a back contact of each relay beyond whereby only the lamp associated with the relay of the highest order picked up, is energized.

13. In combination, an indicating board, a series of indicating lamps on said board and arranged in order from first to last, a stick relay for each lamp, a manually controllable contact for each relay, a pick-up circuit for each relay, except the first, including a front contact of the next preceding relay and, in multiple, its own manually controllable contact and those of the relays beyond it, the pick-up circuit of the first relay including its own manually controllable contact, a stick circuit for each relay including other manually controllable contacts, a circuit for each lamp including a front contact of its relay and a back contact of each relay beyond whereby only the lamp associated with the relay of the highest order picked up, is energized, and a manually controllable means effective when operated, and any one of the relays is in attracted position, to energize the relay of the next higher order.

14. In combination, an indicating board, a series of indicating lamps on said board and arranged in order from first to last, a stick relay for each lamp, a manually controllable contact for each relay, a pick-up circuit for each relay, except the first, including a front contact of the next preceding relay and, in multiple, its own manually controllable contact and those of the relays beyond it, the pick-up circuit of the first relay including its own manually controllable contact, a stick circuit for each relay including other manually controllable contacts, a circuit for each lamp including a front contact of its relay and a back contact of each relay beyond whereby only the lamp associated with the relay of the highest order picked up, is energized, and a manually controllable means effective when operated in one manner, and any one of the relays is in attracted position, to energize the relay of the next higher order, and when operated in a different manner to deenergize the relay of the highest order then energized.

FREDERICK W. BRIXNER.
